UNITED STATES PATENT OFFICE.

ISRAEL V. EDGERTON, OF CHICAGO, ILLINOIS, ASSIGNOR TO PALACE POULTRY CAR COMPANY, OF CHICAGO, ILLINOIS, A CORPORATION OF ILLINOIS.

POULTRY CAR.

Application filed May 19, 1927. Serial No. 192,609.

This invention relates to the art of railway cars designed for the transportation of live stock, and has reference more particularly, as to the improvements forming the subject-matter of the invention, to what are known as poultry cars.

Poultry cars as at present constructed are usually equipped with tiers of coops disposed on opposite sides of a central longitudinal aisle, and formed with a central room or compartment constituting living and sleeping quarters for the attendant in charge of the shipment and for the storage of feed. In the upper portion of this central compartment and directly beneath the roof of the car is customarily located a water tank, with pipes running therefrom toward the ends of the car for supplying water to the stock. Such water tanks are commonly provided with one or more filling spouts that extend from the top of the tank upwardly through the roof of the car, and are equipped with lids or covers.

My present invention has to do with this water tank and its filling spout. It has been found by experience that, under the more or less sudden and jerky stopping and starting movements of the car, the water in the tank surges violently from side to side of the latter and the blows of the water against the side walls of the tank impose considerable strain, sometimes causing the sides to spring and leak. One object of my invention is to provide a simple, efficient and inexpensive means in the general nature of a baffle for checking the surging action of the water.

It has heretofore proved a matter of some difficulty to make a tight, cinder-proof and waterproof joint between the filling spout or chute of the tank and the roof of the car, so as to prevent cinders and rain from beating into the latter at such joint. One object of my present invention is to provide an improved sealed joint between the filling spout or chute and the roof of the car, such as will effectively seal the joint against the access of cinders and water from the outside, and thus prevent the access of cinders to the water tank and the rotting of the wooden roof boards around the filling spout.

A still further object is to provide an improved and highly efficient closure for the filling spout or chute.

The manner and means by which the above-stated objects and advantages are secured

will be readily understood by those skilled in the art from the following detailed description, taken in connection with the accompanying drawings wherein I have illustrated practical and preferred embodiments of the invention, and in which—

Fig. 1 is a top plan view of the central portion of the car roof directly overlying the water tank, showing the latter and its baffle by dotted lines beneath the roof; 65

Fig. 2 is a transverse vertical section through the portion of the roof shown in Fig. 1, on the line 2—2 of the latter figure, with the underlying water tank in side elevation, partly broken out and in section; 70

Fig. 3 is a horizontal section through the water tank on the line 3—3 of Fig. 2, and in the horizontal plane of the upper edge of the baffle; 75

Fig. 4 is an enlarged vertical section, on the line 4—4 of Fig. 1, through the car roof, the upper portion of the filling spout, and the seal and closure of the latter; 80

Fig. 5 is a fragmentary vertical section on a further enlarged scale, through the left hand portion of Fig. 4; 85

Fig. 6 is a view similar to Fig. 5, illustrating a reversal of two overlapping parts;

Fig. 7 is a vertical section on an enlarged scale through the water tank baffle, on the line 7—7 of Fig. 2. 90

Referring to the drawings, 10 designates as an entirety the central roof portion of a poultry car, which includes the usual rafters 11 and roof boards 12. Suitably mounted by any approved means (not shown) directly beneath this central portion of the roof is the rectangular water tank designated as an entirety by 13, said tank consisting of a completely enclosed structure including a roof or cover 14, the sloping sides of which are preferably substantially parallel with the sloping sides of the car roof 10. 95

Disposed within the tank 13 and preferably extending obliquely between diagonally opposite corners of the latter is a baffle. In the preferred form herein shown this baffle comprises a pair of narrow flat wooden strips or planks 15 separated from each other by an intermediate space 16, and united by two pairs of cross cleats 17 nailed or otherwise secured thereto. The cleats 17 are of somewhat greater length than the combined width of the planks 15 and the intermediate space 16, as shown in Fig. 2, so that when the baffle 110

rests on the bottom of the tank there is a space 16' between the lower plank and the floor of the tank about equal in width to the space 16 between the planks. Blocks 18 (Fig. 5) of the width of the cleats 17 may be interposed between the latter in the spaces 16 and 16' for greater strength, if desired, and to assist in breaking up the surging of the water lengthwise of the baffle, but these blocks 18 are not essential. The baffle thus formed does not require to be fastened in or to the tank, but is of a length such that its ends will just straddle the diagonally opposite corners of the tank, as shown in Fig. 3, whereby the side and end walls of the tank support the baffle against lateral displacement in either direction, except for such slight bending movement as may be caused by the pressure of the water when in motion. From the foregoing it will be seen that the described baffle, by partly restricting the rushing movement of the water between the opposite side walls and opposite end walls of the tank greatly reduces the blows of the water on said walls, while at the same time permitting passage of the water through the baffle and thus allowing water to normally stand at equal heights on both sides of the baffle. The water tank baffle above described is not claimed herein, but forms the subject-matter of a divisional application filed January 9, 1929, Serial No. 331,250.

Mounted in the roof 14 of the tank are one or more spouts or chutes extending through the roof of the car, through which the tank is adapted to be filled from overhead. Two such filling spouts are herein shown, and since they are identical in structure, a description of one will suffice. The filling spout herein illustrated is a tapering member 19 of rectangular structure in cross-section, the lower end of which is secured in the roof 14 of the tank by a suitable gasket ring 19^a, while its upper wide end projects through a correspondingly shaped opening in the roof boards 12, fitting and projecting above said opening as shown in Fig. 4. The upper marginal portion of the spout 19 which projects above the roof boards 12 is identified by 19'. Attached to the roof boards 12 around the projecting portion of the spout is a sealing member consisting of a ring 20 of inverted U-shape that embraces the projecting margin 19' of the spout, and a base flange 20' that rests on the roof boards 12 and is attached to the latter as by bolts 21. Between the margin 19' and the sealing ring 20 is preferably interposed a packing 22 of some suitable flexible and compressible substance such as canvas dipped in red lead, which affords a very efficient and durable waterproof seal.

Fig. 6 illustrates a reversal of the structure shown in Fig. 5, wherein the inverted U-shaped sealing ring 20^a is formed as an extension of the upwardly projecting portion 19'

of the spout, and overlaps the upstanding limb of a plain angle ring 23 that is attached to the roof 12. In both of the structures illustrated in Figs. 5 and 6, the joint between the spout 19 and the roof 12 is manifestly effectively sealed against access of water, such as rain beating on the roof or water from within the tank slopping out through the filling spout when the lid or cover of the latter is open. The structure disclosed in Fig. 6 is not specifically claimed herein, but forms the subject-matter of a divisional application filed by me on the 19th day of March, 1928, Serial No. 262,635.

I have also designed an efficient lid or cover for the filling spout or chute, the same consisting of a sheet-metal plate 24 of a size to overlap the sealing ring 20 (Fig. 5) or the sealing ring 20^a (Fig. 6), and flanged on three sides, as shown at 24^a to overlap the latter; a wooden block 25 of a size to interfit the sealing ring 20 or 20^a, and an underlying thin metal plate 26 on the lower side of the block 25; said parts 24, 25 and 26 all being securely united by through bolts 27. To the top of the lid or cover thus formed are attached, conveniently by the same through bolts 27, a pair of hinge straps 28, the rearwardly extending ends of which are curled, as shown at 29 in Fig. 4 to embrace a hinge pintle 30 that extends through holes in a pair of hinge lugs 31 that are welded or otherwise secured to the sealing ring 20. Encircling the hinge pintle 30 between and outside the eyes 29 of the hinge straps are spacing sleeves 32 and 33. The above described structure of lid or cover affords a very strong and snugly fitting closure for the filling spout, the edges of which are effectively sealed by reason of its overlapping engagement with the sealing ring 20.

I claim—

1. The combination with a car roof formed with an opening, and a water tank therebeneath, of a filling spout mounted on said tank and filling and projecting above said car roof opening, a ring attached to said car roof formed with an upstanding flange encircling the projecting portion of said spout, and a packing between said flange and said projecting spout portion.

2. The combination with a car roof formed with an opening, and a water tank therebeneath, of a filling spout mounted in the roof of said tank and filling and projecting above said car roof opening, and a sealing ring having base portion attached to said car roof around said opening and a channel portion overlying and embracing the upper projecting end of said spout.

3. The combination with a car roof formed with an opening, and a water tank therebeneath, of a filling spout mounted in the roof of said tank and filling and projecting above said car roof opening, a sealing ring having

a base portion attached to said car roof around said opening and a channel portion overlying and embracing the upper projecting end of said spout, and a channel shaped packing ring within said channel portion embracing the upper projecting end of said spout.

4. The combination with a filling spout, of a closure therefor comprising a block entering the open upper end of said spout, a metal plate on the upper face of said block having marginal portions overlying the upper edge of said spout, a metal plate covering the under

face of said block, hinge straps overlying said upper plate, and through bolts securing together said block, plates and hinge straps. 15

5. The combination with a car roof formed with an opening, and a water tank there beneath, of a filling spout mounted on said tank extending through and projecting above said opening, a separate sealing ring attached to said roof and surrounding the projecting portion of said spout, and means sealing the joint between said spout and ring. 20

ISRAEL V. EDGERTON.
